UNITED STATES PATENT OFFICE.

THOMAS J. KEHOE, OF TOLEDO, OHIO, ASSIGNOR TO THE WILLYS-OVERLAND COMPANY, OF TOLEDO, OHIO.

DIMMER.

1,390,359.

Specification of Letters Patent. Patented Sept. 13, 1921.

Application filed May 23, 1917. Serial No. 170,473.

To all whom it may concern:

Be it known that I, THOMAS J. KEHOE, a citizen of the United States, residing at Toledo, in the county of Lucas and State 5 of Ohio, have invented certain new and useful Improvements in Dimmers, of which I declare the following to be a full, clear, and exact description.

This invention relates to automobile 10 headlights and more particularly to the dimmers used to temporarily cut off a portion of the light projected from said headlight. The object of this invention is to provide a new and simplified dimmer 15 construction for automobile headlights, which may be readily and conveniently operated by the driver of an automobile. A further object is to provide a screen adjustable around the light source to intercept the light passing to the reflector. A further object is to provide a dimmer which 20 will cut off the reflected rays of the headlight only.

Further objects, and objects relating to 25 economies of manufacture and details of construction, will definitely appear from the detailed description to follow.

A structure constituting a preferred embodiment of my invention, is illustrated in 30 the accompanying drawing forming a part of the specification, in which:

Figure I shows the front end of an automobile having headlights embodying my invention;

Fig. II is an enlarged, sectional view on 35 the line II-II of Fig. I showing the dimmer in non-dimming position;

Fig. III shows the manner in which dimmers are mounted on a common operating 40 rod;

Fig. IV shows the means for actuating the dimmer shaft and is taken on the line IV-IV of Fig. III;

Fig. V is a fragmentary view in side elevation showing the dimmer in dimming 45 position with reference to the light bulb;

Fig. VI is a front elevation of the dimmer screen;

Fig. VII is a detail sectional view taken on 50 line VII-VII of Fig. V; and

Fig. VIII is a section taken through a modified form of dimmer screen.

In the drawings, similar reference characters refer to similar parts throughout the

several views, and the sectional views are 55 taken looking in the direction of the arrows at the ends of the section line.

Considering the numbered parts of the drawing, the automobile 1 is shown provided with headlights 2. These headlights may 60 be of any ordinary form, the one shown having an outer shell 8 of parabolic form, and an inner shell 9, of similar shape, which forms the reflector. Axially positioned within the casing is an electric light bulb 65 socket 3, which is adapted to receive an electric light bulb 4. The electric bulb is so positioned that it is approximately at the focal point of the parabolic reflecting surface.

The dimmer screen consists of a resilient 70 trip 5 of metal or other suitable material, which is coiled in the form of a spiral, the inner end of the coil terminating some distance from the center of the coil. The outer 75 end of the spiral is bent away at 6 in the direction of the diameter of the spiral. The screen is positioned within the reflector 9, and normally lies in such a position that the plane of its greatest area is angularly disposed with relation to the axis of the lamp 4 and the central aperture of the coil is adjacent the outer end of the light bulb. The reflector is slotted at 10 to permit of pivotal motion of the screen.

The operating mechanism comprises a rock shaft 7 extending between the headlights and having its ends entering the outer casings of the headlights. The end 6 of each spiral 5 is rigidly connected to one end 90 of the rock shaft 7. Radially extending from rock shaft 7 are two arms 11 and 12. The arm 11 is connected at its end to a spring 13, the other end of which is fixed in any suitable manner. The arm 12, which 95 extends from shaft 7 at an angle to the arm 11, is pivotally connected to an operating rod 14, which extends through the dashboard and is provided with a suitable handle 15, the rod being notched at 16 to engage the edge of the opening through the dash and hold the screens in dimming position.

As shown in Fig. II, the normal non-dimming position of the screen is free of the 105 lamp and it is held in this position through the tension of the spring 13, it being apparent, however, that the resiliency of the coil

strip 5 also provides inherent means therein for normally retaining the dimmer in retracted non-dimming position. When the 5 operating rod 14 is pulled inwardly, the arm 12 rocks the shaft 7 against the tension of the spring 13, which causes the resilient spiral 5 to engage the light bulb 4 and the outer spirals of the screen pass over the side of the bulb. As the inner spirals have a 10 diameter less than that of the light bulb, they are held stationary. The result is a cone-shaped screen extending around the sides of the bulb, the end of the bulb being left exposed. As the greater part of the projected 15 light comes from the rays reflected from the walls of the reflector when the sides of the bulb are screened and such rays are intercepted, the intensity of the light is materially diminished. In the modification 20 shown in Fig. VIII, the central aperture is covered by means of wire gauze 17 which serves to further dim lights.

Considering Fig. II of the drawings, it 25 will be seen that in its normal non-dimming position the spiral screen 5 occupies but very little space and lies entirely in front of the lamp and in the central part of the casing, so that it does not intercept or interfere with any of the rays of reflected light 30 coming from the reflector. When the screen is brought to the dimming position, shown in Fig. V, the inner spiral being engaged by the end of the lamp and held, and the other spirals telescoping one over the other and 35 embracing the sides of the lamp, cut off substantially all the light which would otherwise pass from the light source to the reflector, so that practically all of the reflected 40 light is eliminated and nothing is left but the direct rays from the light source, which are not of sufficient intensity to be objectionable.

I am aware that the embodiment of my invention shown and described is susceptible 45 of considerable variation without departing from the spirit of my invention and, therefore, I desire to claim the same broadly. I have found, however, that this particular embodiment is desirable from many standpoints, and therefore, I desire to claim the 50 same specifically as well as broadly, as will appear from the appended claims.

Having thus described my invention, what I claim as new and desire to secure by Letters Patent is:

1. In a device of the class described, the combination of a reflector, a light source within said reflector, and a resilient spiral strip adapted to be extended over said light 60 source to screen lateral rays therefrom.

2. A dimmer for headlights comprising a ribbon of metal coiled to form a spiral, the inner end of said spiral terminating at a 65 distance from the center thereof and forming a central opening, and the outer end

of said spiral being bent outwardly to form a supporting member, and means for actuating said spiral.

3. A headlight comprising a casing, a lamp within said casing, and dimming 70 means within said casing adapted to be forced against the lateral portions of said lamp and limited in its movement thereby.

4. In a headlight having a reflector, and an electric light bulb within said reflector, the combination therewith of a dimmer of resilient material adapted to normally assume a contracted state due to the inherent resiliency of the material thereof and adapted to be expanded around said bulb to 80 screen lateral rays of light therefrom.

5. In a device of the class described, the combination of a headlight comprising a reflector and a light bulb therein, and a resilient metallic strip wound in a flat spiral 85 and normally disposed in front of said light bulb, the inner convolution thereof being of less diameter than said light bulb, said spirally wound strip being movable to a position embracing said light bulb.

6. In a device of the class described, the combination of a headlight comprising an outer shell, a reflector and a light bulb disposed within said reflector, a rock shaft entering said outer shell, means for rocking 95 said shaft, and a resilient metallic strip secured to said rock shaft and having its free end spirally wound and normally lying in a plane in front of said light bulb whereby when said shaft is rocked the spirally wound 100 strip will embrace the sides of said light bulb.

7. In a headlight, the combination of a light source, a relatively rigid light transmitting member surrounding said light 105 source, a collapsible dimmer movable bodily toward and away from said light transmitting member and having a portion thereof adapted to be engaged by said member during movement into dimming position. 110

8. A dimmer for a headlight having a lamp, said dimmer comprising an expandable coiled spring, one end of which is adapted to be held by the lamp and the other moved relative thereto to spread said spring around 115 said lamp.

9. In a device of the class described, the combination of a reflector, a light source in said reflector, and a resilient metallic spiral normally supported in front of said 120 light source and adapted to be expanded over said light source to screen lateral rays therefrom.

10. A dimmer for electric headlights comprising a coil of resilient material adapted 125 to embrace a light to serve as a dimmer therefor, and means for moving said coil into dimming position.

11. In a headlight, the combination of a 130 reflector, an electric light bulb within said

reflector, and a metallic spiral dimmer having a central opening therein and adjustable by expansion around said bulb to screen the lateral rays from said light.

5 12. In combination, a light bulb, a dimmer therefor comprising a resilient spirally wound member having a contracted and inoperative position out of contact with said bulb, means for putting said member under 10 tension by expanding it in contact with said bulb, said member tending to return to its retracted inoperative position due to its own resiliency, and means to assist in the return of said member to inoperative position.

13. In a headlight construction having a

light source and a reflector, the combination therewith of a dimmer including a spirally wound strip adapted to surround said light source and intercept the rays of light from 20 said source to said reflector, one end of said strip being extended through a slot in the reflector, and a pivotal support for said end.

14. An automobile headlight dimmer comprising a spiral strip of material provided 25 with an extension arm forming a support therefor, and means adapted to swing said arm to extend the spiral around an electric light bulb.

In testimony whereof I affix my signature. 30

THOMAS J. KEHOE.
